Inventor:

Morris Du Bois

by Atty. Mr. J. Sprague

UNITED STATES PATENT OFFICE.

MORRIS DU BOIS, OF BRIGHTON, MICHIGAN.

HALTER.

SPECIFICATION forming part of Letters Patent No. 309,611, dated December 23, 1884.

Application filed May 2, 1884. (No model.)

To all whom it may concern:

Be it known that I, MORRIS DU BOIS, of Brighton, in the county of Livingston and State of Michigan, have invented new and useful Improvements in Halters; and I do hereby declare that the following is a full, clear, and exact description thereof, reference being had to the accompanying drawing, which forms a part of this specification.

10. This invention relates to certain new and useful improvements in the construction of halters.

15. The object of this invention is the construction of a halter to be used especially in breaking colts and vicious animals, so that they can easily be led by the halter and taught to stand when tied; and the invention consists in the peculiar construction of the parts, all as more fully hereinafter set forth.

20. In the accompanying drawing, which forms a part of this specification, A represents the nose-ring, which is elliptical in form, and is formed preferably of round wire of any suitable dimensions, at the rear end of the ring there being formed a loop for the reception of the halter-strap B. At the sides of the nose-ring A are formed loops a, in which are secured the ends of the head-strap C. If desired, a throat-latch may also be secured and form a part of the head-strap, although such is not necessary.

25. In practice the device is placed upon the horse or animal with the nose through the nose-ring, as in the application of the ordinary halter, with the halter-strap behind the chin. This ring being rigid and non-elastic will hang loosely around the nose of the animal until it begins its capers, such as pulling, jerking, or forging ahead, when the person having hold 30 of the halter-strap can, by a slight twitch thereof, compel the ring to turn, violently bringing the shorter diameter of the ring across the nose of the animal, so as to compress his nostrils and compel him to stop if

he is inclined to go ahead. If he is inclined 45 to pull back, a little oscillation or side whipping of the nose-piece around his nose will, in the manner above described, cause him to again stand still, and it has been shown by actual use of this device that a vicious colt or 50 older animal can in the space of a very few minutes be taught to lead gently by the halter and to stand quiet when hitched. After being so broken to the halter, the common halter may be used upon the animal. 55

I am aware that nose-rings for halters have been made of flexible material, such as rope or leather, and do not claim such as forming part of my invention; but I am not aware that a rigid elliptical nose-ring has ever before been 60 used.

While I have described the nose-ring as being made of wire and prefer such to any other, yet it is evident that it may be made of any unyielding substance which would make a 65 rigid ring, without departing from the spirit of my invention. By the term "rigid ring" I mean one that will retain its shape under all ordinary strain, so that it will not readily give when twisted around the animal's nose. 70

What I claim as my invention is—

1. The rigid elliptical nose-ring A, provided at its rear end with a loop to receive the halter-strap, and at its sides with loops a, for receiving the ends of the head-strap, substantially 75 as described.

2. A halter consisting of the rigid elliptical nose-ring A, provided with a loop at its rear end and loops a at its sides, the halter-strap B, secured to the loop at the end, and the head-strap C, having its ends secured in said loops a, substantially as and for the purposes specified. 80

MORRIS DU BOIS.
